CRUTCH

Filed Feb. 3, 1945

Inventor:
Teronett Clemens
David Manly Keller,
attorney.

UNITED STATES PATENT OFFICE

2,437,076

CRUTCH

Jerome H. Clemens, Chicago, Ill.

Application February 3, 1945, Serial No. 575,997

9 Claims. (Cl. 135—53)

1

My invention relates to improvements in crutches. One object of my invention is to provide a crutch having a spur connected thru a rod to the hand hold of the crutch which is journaled or pivoted in the bows of said crutch, said spur being capable of movement down or up under the influence of the hand by a movement of said hand hold, clockwise or counterclockwise about its axis. The movement of the rod connected to the spur being effectuated by cam means translating the partial rotary movement of the hand grip, into reciprocal movement of the spur.

Another object of my invention is to provide an improved crutch of the aforementioned character in which the spur is interchangeably and removably secured.

Another object of my invention is to provide an improved crutch of the aforementioned character having a prod or a spike adapted to be protruded beyond the end of the crutch when necessary, to prevent slipping, and also capable of having the spur retracted within the said crutch when not needed, or when it is desired to avoid injury to a surface upon which the crutch is operated.

One feature of the invention consists in providing means for protruding and retracting the prod by virtue of cam actuated means providing at the same time means for locking the prod or spike in protruded position, adapted to effectively bite into a sleety or icy surface.

A further object of my invention is to provide an improved crutch of the aforementioned character which is practical and efficient in its construction and operation, and of such simple elemental construction as to permit economical manufacture thereof in quantity production.

Other features, and ancillary objects, inherent in my invention will become apparent from an examination of the accompanying drawings, having particular reference to the ensuing description, in which like symbols are used to designate like parts, and in which:

Fig. 1 represents a front view of my invention partly in section.

Fig. 2 represents a side view thereof in operative position.

Fig. 3 represents an enlarged fragmentary showing of the cam motivating means used in connection with my improved crutch when in inoperative position.

Fig. 4 is an enlarged longitudinal cross-sectional view taken, substantially, on the line 4—4 of figure 3.

2

Fig. 5 is a slight modification of my invention used in connection with a crutch of different configuration.

Referring to the drawings, 6, generally, designates a crutch which is constructed in accordance with the teachings of my invention, hereinafter to be more clearly elucidated. The said crutch is provided with an under arm rest 7 which may be suitably padded, and the bowed out supports 8, which merge into a leg portion 42. The said supports 8 are provided with the pad 9 in order to receive, rotatably therebetween, the hand hold or support 14, which is integrally formed with a web 15 of bell-crank shape, and which is provided with a slotted portion 38 terminating in an offset recess portion 39 having a curved portion 40 to facilitate releasing the pin 20.

To the slotted portion 38, I attach a rod member 18 which has a fork-like extension furnishing the slotted recess 19 to fit the web 15 and being secured thereto by virtue of a rivet, or other suitable means 20. The fork-like rod portion 18 terminates in a reduced rod portion 26 which is suitably guided in the bored recess 24. The rod 26 terminates in an enlarged portion 25 to furnish an additional bearing at the extreme foot of the leg 42 of the crutch 6. This enlarged portion 25 is suitably tapped in order to receive the conically-shaped prod or spike 27 which has a reduced threaded extension 28 to be secured removably to the tapped hole in the section 25.

The lower portion or foot of the leg 42 of the crutch is suitably encased in a resilient, or rubber tip 29. The crutch leg 42 is provided with an enlarged counterbored portion 23 in order to furnish clearance and relieve the frictional contact which would otherwise exist between the rod 26 if the enlarged counterbore 23 were not present.

The central portion of the crutch is provided with a counterbored section 22 in which is housed a suitable spring element 21 abutting against the end of the counterbore 22; the spring 21 being confined between the bottom of the counterbore 22, and the shoulder on the portion 18 of the extendable and retractable rod 26.

The bowed portions 8 of the crutch below the pad 9 form a recess 16 which is also cut out or relieved as indicated at 17 in order to provide sufficient clearance for the movement of the cantilever-like cam means 15 cut out for lightness as shown at 41.

It is to be noted that the body 13 of the screw 10, at the end thereof 12 furnishes a suitable seat against the pad 9 so as to furnish a sufficient clearance for the smooth operation of the

rotatable hold or grip 14. The screw 10 being thread seated by virtue of its threaded extension 11.

The single crutch, or a pair thereof, may be positioned with respect to a wearer so that it would require manipulation of the hand hold or grip 14 clockwise to effectuate the protrusion of the prod or spike 27, and conversely to be rotated counterclockwise to retract the same, or the situation may be reversed; i. e. the hand hold or grip may be rotated counterclockwise to protrude the prod or spike, or clockwise to retract it. It all depends on how the crutch is orientated when the user is relying upon it to function efficiently, yet it is entirely optional with him to select which 15 directional method of operation or rotation he prefers.

In Figure 3, I indicate the crutch in its normal position when the prod 27 is retracted, thus the crutch tip 29 is operative and prevents mar- 20 ring of surfaces on which it may operate.

In Figure 2, the position is indicated wherein the prod is protruded for effective operation on slippery, icy, sleety or similar surfaces upon which an individual using it may be compelled 25 to walk.

Some forms of crutches are made up with the bowed out portions 8 running almost the entire length of the crutch, in fact almost to the very bottom as shown in Figure 5, wherein the bowed out portions terminate at 33 where they are brought together and form the leg 35. In this particular case the rod portion 24 may be of one continuous length having a prod 37 at its terminus and being secured to a guide bushing 30 by virtue of a pin or set screw 31, the spring 32 being confined between the bearing or bushing 30 and the bottom of the counterbore 34, the guide at the other end indicating the rod 24 operating within the bore 43. The upper portion of the rod 24 is similar to that indicated in Figures 1 to 4, and operates in the same manner as heretofore elucidated for Figures 1, 2, 3, and 4. The crutch foot carries a tip 36 of resilient material.

It should be noted that the portion 40 is shallow so as to permit unlocking of the pin 29 from engagement with the portion 39 by slight pressure in a counterclockwise directional movement (see Fig. 2) when it is desired to retract the prod.

I believe, I have described rather succinctly the nature and operation of the crutch improvement I have created, and inasmuch as the same is susceptible of various improvements and modifications, I reserve the right to all such improvements and modifications coming within the scope and spirit of my invention, as well as those embodied in the accompanying drawings, and also those falling within the purview of the foregoing disclosure.

Having thus described and revealed my invention, what I claim as novel and desire to secure by Letters Patent, is:

1. In a crutch having a tip, bowed supports, cam actuated prod means projectable beyond said tip, and a hand hold rotatably mounted between the said bowed supports, the said hand hold provided with an extension; slotted cam means in said extension, a forked member mounted on the upper end of said prod means and slidably secured to the extension of the said hand hold, and pin means articulately securing the said forked member to the said slotted cam means.

2. In a crutch having a tip, bowed supports, cam actuated prod means projectable beyond said tip, and a hand hold rotatably mounted between the said bowed supports, the said hand hold provided with an extension; slotted cam means in said extension, a forked member mounted on the upper end of said prod means and slidably secured to the extension of the said hand hold, pin means articulately securing the said forked member to the said slotted cam means, and a spur removably secured to the said prod means.

3. In a crutch having a tip, bowed supports, cam actuated prod means projectable beyond said tip, and a hand hold rotatably mounted between the said bowed supports, the said hand hold provided with an extension; slotted cam means in said extension, a forked member mounted on the upper end of said prod means and slidably secured to the extension of the said hand hold, and pin means articulately securing the said forked member to the said slotted cam means, the said prod means adapted to be projected and retracted by inverse rotary movements of the said hand hold.

4. In a crutch having a tip, bowed supports, cam actuated prod means projectable beyond said tip, and a hand hold rotatably mounted between the said bowed supports, the said hand hold provided with an extension; slotted cam means in said extension, a forked member mounted on the upper end of said prod means and slidably secured to the extension of the said hand hold, pin means articulately securing the said forked member to the said slotted cam means, and a spur removably secured to the said prod means, the said prod means adapted to be projected and retracted by inverse rotary movements of the said hand hold.

5. In a crutch having a tip, bowed supports, cam actuated prod means projectable beyond said tip, a pivot element secured to the said bowed supports, and a hand hold rotatably mounted on the said pivot element and confined between the said bowed supports, the said hand hold provided with an extension; slotted cam means in said extension, a forked member mounted on the upper end of said prod means and slidably secured to the extension of the said hand hold, and pin means articulately securing the said forked member to the said slotted cam means.

6. In a crutch having a tip, bowed supports, cam actuated prod means projectable beyond said tip, a pivot element secured to the said bowed supports, and a hand hold rotatably mounted on the said pivot element and confined between the said bowed supports, the said hand hold provided with an extension; slotted cam means in said extension, a forked member mounted on the upper end of said prod means and slidably secured to the extension of the said hand hold, pin means articulately securing the said forked member to the said slotted cam means, and a spur removably secured to the said prod means.

7. In a crutch having a tip, bowed supports, cam actuated prod means projectable beyond said tip, a pivot element secured to the said bowed supports, and a hand hold rotatably mounted on the said pivot element and confined between the said bowed supports, the said hand hold provided with an extension; slotted cam means in said extension, a forked member mounted on the upper end of said prod means

and slidably secured to the extension of the said hand hold, and pin means articulately securing the said forked member to the said slotted cam means, the said prod means adapted to be projected and retracted by inverse rotary movements of the said hand hold.

8. In a crutch having a tip, bowed supports, cam actuated prod means projectable beyond said tip, a pivot element secured to the said bowed supports, and a hand hold rotatably mounted on the said pivot element and confined between the said bowed supports, the said hand hold provided with an extension; slotted cam means in said extension, a forked member mounted on the upper end of said prod means and slidably secured to the extension of the said hand hold, pin means articulately securing the said forked member to the said slotted cam

10

15

means, and a spur removably secured to the said prod means, the said prod means adapted to be projected and retracted by inverse rotary movements of the said hand hold.

9. The structure defined in claim 1, further characterized by an offset recess at the terminus of said slotted cam means adapted to engage releasably the said pin means.
